UNITED STATES PATENT OFFICE.

JOHN ZILLIOX, OF ORCHARD PARK, NEW YORK, ASSIGNOR TO PARK METALWARE CO.
INC., OF ORCHARD PARK, NEW YORK.

WIRE CONNECTER.

Application filed July 19, 1922. Serial No. 576,081.

This invention relates to a coupler or connector which is more particularly intended for connecting electric wires or conductors without soldering, although the same may 5 be used for other analogous purposes.

One of the objects of this invention is to provide a connector of this character which permits of not only properly connecting wires of the same diameter but wires of 10 widely different diameters as well without liability of producing an uneven strain on any of the parts which otherwise would be liable to distort the same and impair their efficiency.

15 Another object of this invention is the provision of such a connector which operates as a lock to prevent loosening of the nuts and bolts which couple the plates forming the main elements of this connector or fastener and thus insure a firm and reliable connection between the respective wires.

Further objects of the invention are to so construct the connector that the same permits a connection between wires to be made 25 in less time than heretofore, and also to enable one man to effect such connections and thus dispense with an assistant and effect a considerable economy in this class of work.

In the accompanying drawings: Figure 1 30 is a side elevation of a connector embodying my invention and coupling two wires of different diameters. Figure 2 is a cross section taken on line 2—2, Fig. 1. Figure 3 is a perspective view of a pair of clamping plates forming part of my improved connector.

Similar characters of reference indicate corresponding parts in the several views.

In its general organization, the connector 40 made in accordance with my improvements comprises two clamping plates adapted to engage opposite sides of the wires to be coupled and tightening means whereby said plates are drawn together and caused to firmly grip the wires between the same and effect a reliable electrical connection therewith.

To illustrate an advantageous feature of this improved connector, the same is shown 50 in the drawings applied to two wires 10 and 11 of different diameter which have their coupled parts arranged parallel and side by side.

55 Each of the two clamping plates 12, 12, of the connector preferably consists of a

piece of resilient sheet metal which is stamped or bent by suitable dies, so that the same is provided with three longitudinal parallel corrugations 13, 14, 15. The two corrugations 13, 15 arranged adjacent to the 60 longitudinal edges of the plate are provided on their inner sides with longitudinally grooved jaws 16 which are preferably V-shaped in cross section. The central corrugation 14 of each plate is preferably somewhat wider than the edge corrugation and bulges outwardly so as to present a convex bearing face 17 on the outer side of this corrugation.

The tightening means preferably consists 70 of two bolts which are arranged side by side lengthwise of the plates and each having its body or shank 18 passing transversely through corresponding openings 19 formed in the central corrugations of the plates near 75 one end thereof and engaging the inner side of its head 20 with the convex bearing face of one of the plates while its screw nut 21 engages its inner side with the convex bearing face of the other plate. The openings 80 19 in the plates are enlarged in the direction of the width of the same in order to permit these plates and bolts to rock the requisite extent transversely upon each other to enable the jaws of the plates to adapt themselves to the surfaces of the wires to be connected.

In the operation of connecting two wires with this connector, the wires are placed between the plates and opposite sides respectively of the tightening bolts, and the cooperating jaws on the corresponding longitudinal edges of the two plates are engaged with opposite sides of one of the wires. The bolts are now tightened so that the jaws of 95 each pair on the opposing edges of both plates are firmly drawn against the opposite sides of the respective wire and caused to form a reliable electrical connection therebetween. By reason of the V-shaped formation of the faces on the gripping jaw, each of the same engages with the wire along two lines of contact so that when the coupling of two wires is completed, each wire will be gripped at four different points and thus 100 insure a good electrical connection.

As the clamping plates adapt themselves to the surface of two wires of different diameter, these plates tilt on the body of the bolts during which time the heads and nuts 110

of the latter rock on the convex outer bearing surface of the plates and adapt themselves thereto, so that each head and bolt engages over its entire inner side with the 5 respective bearing surface. By this means a straight pull is exerted upon each of the tightening bolts which enables the same to be employed most effectively and also prevents the body, head or nut of a bolt from 10 being bent or distorted and not only rendered less effective but also preventing the bolts from being used over again if the occasion requires it.

Moreover, by providing the plates centrally with outwardly bulging corrugations 15 which are engaged by the heads and nuts of the bolts, these corrugations form springs which are put under tension when the bolts are tightened and which operate as locks 20 to prevent the nuts and bolts from becoming loose.

It will be apparent from the foregoing, that this device is adaptable to a wide range 25 of wires of various diameters and that it

may be put in use easily and expeditiously 25 and without liability of bending the bolts, stripping the threads of the same, or putting any undue strain on any of its parts.

I claim as my invention:

A wire connector comprising two plates 30 each of which is bent from a piece of sheet metal to form three parallel corrugations having convex outer sides and concave inner sides, the central corrugation of each plate being wider than the end corrugations on 35 opposite sides thereof and each central corrugation having an opening, said plates being assembled with the concave sides of their end corrugations facing each other and adapted to engage opposite sides of the wires 40 to be gripped, and a clamping bolt passing through the openings of the central corrugations and bearing with its head against the convex side of the central corrugation of one plate and with its nut against the convex side of the central corrugation of the other plate.

JOHN ZILLIOX.
